United States Patent Office.

ANDREW DICKEY, OF ALBANY, NEW YORK.

Letters Patent No. 80,814, dated August 11, 1868.

IMPROVEMENT IN SAD-IRON SUPPORT FOR STOVES.

The Schedule referred to in these Letters Patent and making part of the same.

TO ALL WHOM IT MAY CONCERN:

Be it known that I, ANDREW DICKEY, of Albany, in the county of Albany, and State of New York, have invented an Improved Sad-Iron Support for Stoves; and I do hereby declare that the following is a full, clear, and exact description thereof, reference being had to the accompanying drawings, making a part of this specification, in which—

Figure 1 is a vertical section through a section of stove-plate adapted for the illuminating-section of a base-burning stove, showing the improved sad-iron support, and a sad-iron in position upon it for being heated.

Figure 2 is a front view of the stove-plate section, with one sad-iron support attached.

Figure 3 is a perspective view of the sad-iron support, detached from its stove-plate.

Similar letters of reference indicate corresponding parts in the several figures.

This invention relates to a new and useful improvement, which is designed for adapting a parlor-stove or heater to serve, when desired, as a means whereby sad-irons can be conveniently heated, and when it is not desired to heat such irons, the device, which is necessary to support them in position upon the side of the stove, can be readily removed.

The invention consists in a bracket or support for sad-irons, which is adapted for being attached to the side of a stove-plate section, in a position which will allow sad-irons to be placed in front of the illuminating-openings or doors of a base-burning stove, in the best possible position for heating them, said bracket being so constructed that when it is not in immediate use it can be readily detached from the stove-plate section, so as not to impair the appearance of the stove as a parlor-heater, as will be hereinafter explained.

To enable others skilled in the art to understand my invention, I will describe its construction and operation.

The stove-plate A, which I have represented in the accompanying drawings, is one of several sections which are designed for enclosing the fire-chamber of a base-burning stove, and forming what is known as the illuminating-section of such a stove. This plate has three door or window-openings, C, through it, which expose to view the light of the fire in the fire-chamber of the stove, which openings are surrounded by flat, projecting surfaces, well adapted for receiving against them the flat surfaces of sad-irons.

In a stove of the description to which my invention has particular reference, the plates A are arranged around a vertical centre, and stand in slightly-inclined positions. They are not, however, sufficiently inclined to afford a support for holding in place a sad-iron or other object placed against them.

B represents a bracket, which is constructed with two short, upturned arms, *a a*, and also with a notched arm, *b*, which latter projects from the inner side of the bracket, and is notched so as to form a hooked or self-fastening for allowing the bracket to be firmly attached to the stove-plate A, at the base of any one of the doors C.

An opening, *c*, is made through the stove-plate A at the base of each door C, which opening is adapted for receiving through it the hooked or notched arm *b* of the bracket B, the said arm being introduced through the opening *c'*. The bottom edge of this opening will receive the notch in the arm, as shown in fig. 1, and thus firmly retain the bracket B in proper position at the base of one of the openings C, to receive and support a sad-iron, as indicated in red lines in fig. 1.

To remove the bracket B, it is only necessary to lift it slightly and withdraw the arm *b* from the opening through the stove plate.

I have described and particularly intend the improved sad-iron support for base-burning parlor-stoves, but I do not confine myself to its use for this class of stoves, as it is adapted for stoves of various descriptions, having openings through side-plates, which would expose sad-irons placed against them to the heat of the fire.

Having described my invention, what I claim as new, and desire to secure by Letters Patent, is—

A removable sad-iron bracket, B, constructed and adapted for being applied to a stove, substantially as described.
